UNITED STATES PATENT OFFICE.

GUSTAV J. A. TROSTEL, OF MILWAUKEE, WISCONSIN.

RADIATOR ATTACHMENT.

1,181,699.

Specification of Letters Patent.

Patented May 2, 1916.

Application filed March 20, 1915. Serial No. 15,809.

To all whom it may concern:

Be it known that I, GUSTAV J. A. TROSTEL, a citizen of the United States, and resident of Milwaukee, in the county of Milwaukee and State of Wisconsin, have invented certain new and useful Improvements in Radiator Attachments; and I do hereby declare that the following is a full, clear, and exact description thereof.

10 My invention consists in steam and hot-water radiator attachments similar to the one herein particularly set forth with specific reference to the accompanying drawings and pointed out in the claims of this specification, its object being to provide simple, economical, efficient and sanitary means for supplying moisture to atmosphere in apartments heated by radiators of the above description, and for collecting dust 20 particles floating in said apartments.

Figure 1 of the drawings represents a perspective view partly in section of an attachment in accordance with my invention applied to a hot-water radiator, and Fig. 2, 25 a partly sectional view of a fragment of the attachment.

Referring by numerals to the drawings, 3 indicates a fragment of a hot-water radiator upon which an attachment in accordance 30 with my invention is supported, but a similar attachment is applicable to a steam-radiator.

The attachment comprises a skeleton-frame of any suitable construction, a trough-like reservoir in connection with the frame, to extend longitudinally of the same in rear of the radiator below its upper end, and a frame-covering of absorbent material that extends into the trough. Burlap, toweling 40 or other textile material will be found suitable for the frame-covering.

The frame herein shown comprises end pieces 4 and a series of rods 5, 5', connecting the same. The trough 6 is supported by the 45 end pieces of the frame to which it is attached in any suitable manner, and the frame-covering sheet 7 may be wound at one end on a frame-rod 5 or otherwise detachably secured to the same, its other end 50 being within said trough. Water is placed in the trough to be supplied to the frame-covering by capillary attraction, its evaporation serving to moisten the surrounding

atmosphere. To best serve as a dust-collector, the covering 7 is permitted to sag 55 between the rods 5 of the frame, as herein shown, and the material of said covering is such that it may be readily cleaned by washing whenever necessary or desirable.

The general construction of the attachment is such that its covered frame forms a deflecting canopy over the radiator upon which it is utilized, and its details of construction are such that there is no downward flap of the sheet of absorbent material 65 from which water may drip, and the heated air from the radiator is deflected outward in a purified and moistened condition. The trough 6 may be variously associated with the aforesaid frame without departure from 70 my invention as herein claimed.

I claim:

1. The combination of a frame supportable on a steam or hot water radiator and which consists of end plates and spaced rods 75 connecting the same, the plates being curved upward from the rear of the radiator toward the front; a water trough associated with the frame in rear of the radiator, and a sheet of absorbent material extending from 80 within the trough over said rods to deflect heated air outward from the radiator in a purified and moistened condition.

2. The combination of a frame supportable on a steam or hot water radiator and 85 which consists of end plates and spaced rods connecting the same, the plates being curved upward from the rear of the radiator toward the front, a water trough associated with the frame in rear of the radiator, and 90 a sheet of absorbent material extending from within the trough over said rods to the front one of the same on which it is wound, the canopy formed by said frame and sheet of absorbent material serving to deflect 95 heated air outward from the radiator in a purified and moistened condition.

In testimony that I claim the foregoing I have hereunto set my hand at Milwaukee, in the county of Milwaukee and State of 100 Wisconsin, in the presence of two witnesses.

GUSTAV J. A. TROSTEL.

Witnesses:

HENRY J. WENZEL,
LOUIS RAHN.
